(57) **CLAIM**

The ornamental design for a portable electric hammer drill body, as shown and described.

DESCRIPTION

FIG. 1 is a front, left, and top perspective view of a portable electric hammer drill body in accordance with our new design;

FIG. 2 is a rear, right, and top perspective view of the portable electric hammer drill body in accordance with our new design;

FIG. 3 is a front elevational view of the portable electric hammer drill body in accordance with our new design;

FIG. 4 is a rear elevational view of the portable electric hammer drill body in accordance with our new design;

FIG. 5 is a top plan view of the portable electric hammer drill body in accordance with our new design;

FIG. 6 is a bottom plan view of the portable electric hammer drill body in accordance with our new design;

FIG. 7 is a left side elevational view of the portable electric hammer drill body in accordance with our new design;

FIG. 8 is a right side elevational view of the portable electric hammer drill body in accordance with our new design; and,

FIG. 9 is a front, left, and top perspective view of the portable electric hammer drill body in accordance with our new design illustrating a state in which environmental structures (a handle and a battery) is attached to the portable electric hammer drill body.

The broken lines in the drawings illustrate the environmental structures or portions of the portable electric hammer drill body which form no part of the claimed design.

1 Claim, 9 Drawing Sheets
